(57) **CLAIM**

The ornamental design for a spindle cover, as shown and described.

DESCRIPTION

FIG. 1 is a front elevational view of a spindle cover;
FIG. 2 is a rear elevational view thereof;
FIG. 3 is a top view thereof;
FIG. 4 is an underneath view thereof;
FIG. 5 is a left side view thereof;
FIG. 6 is a right side view thereof;
FIG. 7 is a perspective view thereof; and,
FIG. 8 is a cross-section view taken along line 8-8 in FIG. 2. The broken lines in the drawing represent portions of the spindle cover that form no part of the claimed design.
